UNITED STATES PATENT OFFICE.

CHARLES L. WEYAND, OF NEW YORK, N. Y.

ORNAMENTED DRESS MATERIAL AND PROCESS FOR PRODUCING THE SAME.

Application filed February 20, 1926. Serial No. 89,815.

My invention relates to new and useful improvements in ornamented dress materials and to the process for producing the same. The present ornamented article is produced by a mechanical process that was 5 heretofore produced only by hand and therefore at a relatively great expense.

At the present time there is a great demand and the styles call for silk or cotton 10 dress goods which are highly decorated, or, in other words, covered with large colored motifs that are imprinted on the silk or cotton material. These decorations or motifs are impressed upon the goods by subjecting 15 the same to individual rollers that make up a composite form, the individual rollers having thereon parts of the complete designs or motifs so that the separate colors may be impressed upon the goods to make 20 up the composite design and reproduce the same at regular intervals throughout the cloth.

There is also a demand for silks and cottons, having various motifs formed thereon 25 with the addition of what is known as "crackle", which might be explained as non-geometrical or conglomerate lines or designs extending across the goods and across the previously imposed motifs.

30 This latter form of designing is known as "hand batik" and produced by the batik or wax resist process, the material being covered with wax and subjected to different dyes or colors, the wax preventing the dyes 35 from coloring the major portion of the cloth and producing irregular outlines, forming an odd and colorful effect.

This "batik or wax resist process" has heretofore been accomplished only by hand, 40 resulting in a high price for the material inasmuch as the labor is more or less the work of an artist.

In printing silk in the ordinary way as 45 formerly described, the several colors are severally imposed upon the cloth, the various colors forming the different motifs and decoration, the several colors meeting at the various edges of the motifs. And an object of the present invention is to impose 50 the several colors in their regular manner and to also provide a final roller, having irregular outlines engraved thereon, the outline being simply a non-regular mass of crossing lines, so that the goods still in their wet state will be subjected to this last mentioned roller and the crackle effect appear

through the goods and throughout the various motifs producing an odd and colorful effect which has only been obtained heretofore by the hand batik or wax resist 60 process.

Still another object of the invention is to produce an article simulating in all appearances a hand batik or wax resist process, which is produced by providing a roller 65 with conglomerate lines thereon, so that the motifs and crackle may be imposed upon the silk in the one operation, and while the motifs are still in their wet state thus causing the colors to slightly run, which in conjunction with the irregular lines on what I term the "batik roller" will produce a 70 most colorful and artistic effect heretofore possible only with the wax resist process.

With these and other objects in view, the 75 invention consists in certain new and novel arrangements and combination of parts as will be hereinafter more fully described and pointed out in the claims.

Fig. 1 is a plan view of a piece of cloth, 80 showing how the crackle will appear on the same formed by my improved process;

Fig. 2 is a diagrammatic view showing an arrangement of the rollers for printing 85 the article;

Fig. 3 is a diagrammatic face view of the rollers; and

Fig. 4 is also a diagrammatic view of the roller showing a slightly modified form.

Referring now more particularly to the 90 invention, and for the moment to Fig. 2, I have shown diagrammatically and in its simplest form a drum 1 over which the silk to be printed 2 is passed and which contacts with the first roller 3, on which there 95 is engraved a part of fanciful motif represented as at 4, after which a roller 5 having composite part of the motif thereon prints on the silk its corresponding part. In a like manner the silk will be subjected to 100 the additional rollers, say 6, 7 and 8, the engraving on the various rollers completing the various designs or motifs to be impressed.

As is well known in the ordinary form 105 of silk printing or cotton printing, each of these rollers carry a different color or dye and the entire imprinting of the motifs is such that the colors and shades of the several parts of the motifs meet, but do not 110 overlap or superimpose as otherwise the colors would run into each.

Now with my present invention and the process of carrying it out, I have found that, if I provide a roller 9 that is engraved as at 10 with a mass of conglomerate and irregularly shaped fine lines and subject the cloth in its wet state to this roller a crackle effect will be produced which is so similar to the hand batik or wax resist process that the one form cannot be told from the other. The roller 8 may have any colored ink or dye thereon but preferably this color will be the major color or base used on the cloth. In other words, if dark blue is the predominating color or background of the silk, the crackle will be also of a dark blue. It will be understood that as the dyes are in their wet state that the lines produced by the batik roller will not be sharp ones, but will produce the slight blurring effect that is true of the wax resist or batik process which clearly distinguishes this process from an ordinary printing of lines on the goods. In other words, the lines formed represent the blurring which is known as crackle in the art.

In Fig. 4 I have shown a slightly modified form of producing this crackle effect which consists in forming a plurality of conglomerate lines or irregular lines on say the roller 8 in conjunction with the motif design that is ordinarily placed on this roller.

In other words, instead of using a special roller to produce the crackle, I have found it possible to engrave one of the numerous motive rollers with a crackle design to also produce the crackle effect, but I prefer to use a separate roller as outlined in the preferred form.

From the foregoing, it will be seen that with my improved process I can produce in large quantities in a relatively short time a cloth such as silk or cotton goods with the various motifs and designs thereon with the further addition of a crackle which has heretofore only been produced by what is known as the hand batik process or the wax resist process which necessitate skillful and artistic labor resulting naturally in relatively high prices for the goods at a much reduced cost and at the same time secure the beautiful and artistic results heretofore only obtained by hand.

I am aware that it is old to produce a crackle effect on silk or cotton goods and that it is old to produce printed motifs and

designs on silk and cotton goods, but I am not aware of the producing of a crackle by mechanical means on printed goods while still in their wet state, and I am aware that dark outlines have been produced by a final roller to outline or accentuate design motifs (such as outside of rose leaves, etc.), and I am aware that two wet colors have been printed to touch each other to form a third color as blue and yellow touching to form green; but I am not aware of any process by which a roller gives the fabric a special character of batik, wax resist, or hand made appearance by printing soft wet lines over all the other motifs.

I claim:

1. The process of ornamenting fabrics which consists in subjecting the material to a plurality of printing rollers having designs and motifs thereon, the several rollers forming the composite designs in the colors desired and then subjecting the material while in its wet state to another roller having a plurality of conglomerate and irregularly disposed lines thereon to produce a crackle similar to the crackle produced by the wax resist process.

2. The method of ornamenting silk and cotton goods or other fabrics to simulate the hand batik process which consists in subjecting the material to a plurality of rollers, each of said rollers furnishing its particular color and part of the motif and then subjecting the goods to a final roller whose surface is provided with a mass of conglomerate, irregular and non-directional lines while the goods are still in their wet state to cause the crackle to be superimposed throughout the entire surface of the cloth and intermingling with the various motifs.

3. The process of simulating hand batik or wax resist process for printed goods comprising the subjecting of the material to a plurality of rollers having their surface formed with parts to form the composite design, each of said rollers impressing its individual color, and one of said rollers having a mass of conglomerate lines thereon to thereby form a crackle appearance on the goods while the goods are still in their wet state.

In testimony whereof I affix my signature.

CHARLES L. WEYAND.
